UNITED STATES PATENT OFFICE.

GEORGE E. COX, OF NIAGARA FALLS, NEW YORK, ASSIGNOR TO AMERICAN CYANAMIDE COMPANY, OF NEW YORK, N. Y., A CORPORATION OF MAINE.

CYANAMIDE OVEN.

Application filed June 17, 1925. Serial No. 37,695.

This invention relates to a method of and means for manufacturing calcium cyanamide or lime nitrogen by the reaction between calcium carbide and nitrogen.

5 It has been found in the well-known process of nitrogen fixation by the cyanamide reaction, that the efficiency is greatly increased by an increase in the size of the ovens used, whereby better control of the various factors involved is obtained, and the operating costs are decreased. At the completion of 10 the fixation, the calcium cyanamide is in the form of a block or pig which must be removed from the oven and taken to the point of further treatment. When the pig weighs only 15 a few hundred pounds this is a relatively simple matter but when the pig weighs several tons, difficulties arise. A modern oven may produce a pig about four feet in diameter 20 and six and one-half feet high, weighing say four tons, and the pig must be raised to a point above the oven, say to a height of seven or eight feet, to clear the same. In order to facilitate this, it has been customary to embed 25 in the calcium carbide, before nitrifying, steel rods formed with eyes projecting up above the surface of the subsequently formed pig and providing means for attaching thereto hooks or other devices, whereby the pig 30 of calcium cyanamide was raised up out of the oven.

This was satisfactory in that it provided means for removing the pig, but in practice several difficulties were encountered. The 35 rods, of necessity, were made of heavy stock which was bent at one end to form an eye and at the other end to form an anchorage in the pig. Because of the heavy material it was necessary to forge each piece by hand 40 making the same rather expensive. The nitrification of the calcium carbide in the oven takes place at a relatively high temperature and the steel rods react with nitrogen, becoming weak and brittle. As a result after 45 a rod has been used a short time it becomes so weakened that the weight of the pig being lifted from the oven is often sufficient to cause it to give way, allowing the pig to fall and break. This not only a loss of valuable 50 material but considerable danger of injury to the workman exists. The cost of replacements of rods is, therefore, rather high.

The present invention is intended to ob-

5 viate the difficulties inherent in the removal of pigs from cyanamide ovens, it being among the objects thereof to provide an oven construction which will allow of the ready removal of pigs therefrom, at the same time minimizing the danger of breaking the pigs and injuring the workmen.

60 It is a further object of this invention to provide a method of manipulating the parts of the oven and the pigs so as to facilitate removal of the pigs.

65 In practicing my invention I make the oven of several parts which may be readily fitted together and may be dismantled at will. Instead of making the oven in one piece of cylindrical form I provide a stationary lower portion, consisting of the oven base and side 70 walls rising to a height of approximately one-third of the height of the oven. Connections for nitrogen gas and for the electrode are made in the base portion which is lined 75 with refractory material as usual and is formed with means, at the upper end, for the reception of the upper portion of the oven, which is also lined with refractory material, and forming a gas-tight joint therewith. A cover fits over the top of the upper portion 80 and serves to completely enclose the oven when in operation.

85 The interior of the upper portion is tapered outwardly from the top to the junction with the base portion, and the base portion is tapered outwardly from the bottom to the said junction. As a result the pigs formed therein have a larger diameter at the central portion than at the ends, being somewhat barrel-shaped. In order to remove the 90 pig, the cover is first lifted off and then the upper portion of the oven is removed, or both may be removed simultaneously. The pig is then gripped by a device, operated by a traveling crane, and the pig is raised by the 95 raising of the device. Because of its construction, which is similar in principle to the well-known ice tongs, the weight of the pig increases the pressure of the device and causes it to grip the pig tighter, instead of constituting a strain tending to oppose the effect of the gripping device, as in the means previously used, and it practically eliminates the danger of the pig breaking away from the lifting apparatus.

100 105 In the accompanying drawing, constitut-

ing a part hereof, and in which like reference characters indicate like parts,

Fig. 1 is a vertical, cross-sectional view of an oven made in accordance with my invention, and

Fig. 2 is a cross-sectional view thereof taken along the line II—II of Fig. 1.

The oven consists essentially of a circular sheet metal base 1 having integrally formed side walls 2 and lined both along the sides and bottom with suitable heat insulating material 3, such as sil-o-cel, and an inner lining 4 of refractory material, such as fire brick, or the like, is formed along the walls 2 within the heat insulating lining 3. At the junction between the base and the side walls, a row of refractory brick 5, of special form to make a rounded corner is provided and a row of sector shaped refractory bricks 6, having tapered openings 7 therein, covers the major portion of the base of the oven. The openings 7 are tapered outwardly from the interior of the oven proper down to ducts 8, which are connected to a source of suitable gas, such as nitrogen entering through the side walls. A central opening 9 is provided in the refractory linings of the base and provides a receptacle for the lower end of the electrode used in the oven.

At the upper end of the side walls 2 are secured a series of sector-shaped angle members 10, having projections 11 at the upper surface thereof, the members being joined together to form a complete circle around the upper edge of the side walls 2. S-shaped double angle members 12 are, in a similar manner, joined together to form a ring, being welded or otherwise secured to the angle members 10. The members 12 are adapted to cooperate with angle members 13, secured to the wall or shell 14 of the upper portion of the oven, and having a depending projection formed thereon. A sand seal 15 provides an air tight joint between the two portions of the oven. The upper portion 14 is lined with heat insulating material 16 and refractory material 17, similar to the materials used in the lower portion of the oven. Generally the height of the upper portion 14 is about twice the height of the lower portion 2 of the oven.

Along the top edge of portion 14 is secured a series of angle and S-shaped members 18, similar to those on the upper part of the lower portion 2 of the oven, cooperating with downwardly projecting portions 19, of cover 20, a sand seal 21 being formed at the junction. Eyes 22, are welded or otherwise attached to the top of the shell 14, providing means for raising the same from the base of the oven.

The cover 20 is filled with heat insulating material 23 and has ears 24 formed thereon for facilitating removal thereof. An electrode holder 25 is placed at the center of the cover in alignment with opening 9 and has a terminal 26 electrically connected thereto

for the passage of a current through the holder 25, through the electrode, not shown, and to the base 1 of the oven.

In operation, the shell 14 is placed upon the lower portion 2 the interior of the oven is lined with paper or the like, as is common practice in ovens of this type, and an electrode is placed in opening 9 and holder 25 passing centrally through the oven. Calcium carbide in finely powdered condition, is filled into the oven and the cover 20 is placed thereon. A current is passed through the electrode to heat the same and nitrogen is caused to flow through openings 8 and is distributed, by tapered openings 7 and the crevices between bricks, through the carbide in the oven. Nitrification takes place, resulting in a solid block or pig of calcium cyanamide.

In order to remove the same, a crane is attached to eyes 22 of shell 14 and the upper portion of the oven is lifted off. In order to facilitate the removal thereof, and also the removal of the pig from the oven, the inner side walls 4 and 17 of the lower and upper portions of the oven, respectively, are tapered outwardly to the junction between the two portions. After the removal of shell 14 a gripping device, similar in principle to the well-known ice tongs, is placed over the pig of calcium cyanamide and the tongs lifted by a crane or other device causing the same to firmly and securely grip the pig and raise the pig from the oven. In this type of device the weight of the pig tends to increase the pressure of the gripping device, thereby minimizing the danger of the pig becoming loosened and falling to the ground.

My invention makes it practical to build ovens in larger sizes than heretofore with a corresponding increase in the efficiency of nitrification. The larger units require less labor per ton of material produced, since there are practically no additional operations over those involved in the use of ovens of small size. And, of course, I avoid the use of rods embedded in the pigs for lifting the same from the oven, which rods would be far more expensive for large ovens than for small, for the reason that they must be made of heavier stock by a hand forging method, and they would be exposed to the action of hot nitrogen in the oven for a considerably longer time. It is probable that they could only be used once with safety.

Although I have described my invention setting forth a single embodiment thereof, I am not limited thereto and I may make various changes therein within the spirit and scope of my invention. For instance, I may line the parts of the oven with different materials and in some cases may omit the heat insulating lining or substitute a single lining which will perform the function of the two described. The construction of the sand seals may be changed and a different type of seal

may be used. Other means for introducing and distributing the nitrogen gas may be provided and the connections for the electrode may be different from those described.

5 I have shown an oven in which the upper removable portion is of greater height than the lower portion, but this is not essential as it is apparent that the lower portion may have a greater height. Furthermore, practically the entire wall of the oven may be in 10 the upper portion, the base 1 having only sufficient wall to provide the necessary sealed joint between the two portions of the oven. These and other changes may be made in my 15 invention, the scope of which is defined by the claims appended hereto.

What I claim is:

1. Apparatus for making a block of calcium cyanamide and other materials which 20 comprises an oven base having a side wall section secured thereto an upper side wall section thereon and a sand seal at the junction of said sections.

2. Apparatus for making a block of calcium cyanamide and other materials which 25 comprises an oven base having a side wall section secured thereto an upper side wall section thereon, and a sand seal at the junction of said sections forming an air tight joint 30 therewith.

3. Apparatus for making a block of calcium cyanamide and other materials which 35 comprises an oven base having a side wall section secured thereto an upper side wall section thereon, the upper side wall section constituting the major part of the height of the oven, and a sand seal at the junction of said sections.

4. Apparatus for making a block of calcium cyanamide and other materials which 40 comprises an oven base having a side wall section secured thereto, an upper side wall section thereon, a sand seal at the junction of said sections, and a refractory lining on the inner surface of the oven.

5. Apparatus for making a block of calcium cyanamide and other materials which 45 comprises an oven base having a side wall section secured thereto, a removable upper side wall section thereon, a refractory lining on the inner surface of the oven, and heat

insulating material between the lining and the walls of the oven.

6. Apparatus for making a block of calcium cyanamide and other materials which 55 comprises an oven base having a side wall section secured thereto, a removable upper side wall section thereon, a refractory lining on the inner surface of the oven and heat insulating material between the lining and the walls of the oven, the said lining and insulating material of the upper side wall section being removable therewith.

7. Apparatus for making a block of calcium cyanamide and other materials which 60 comprises an oven base having a side wall section secured thereto, a removable upper side wall section thereon, a refractory lining on the inner surface of the oven and a plurality of inlets for nitrogen gas in the lining 65 of the oven base.

8. Apparatus for making a block of calcium cyanamide and other materials which 70 comprises a removable oven base having a side wall section secured thereto, a removable upper side wall section thereon, a refractory lining on the inner surface of the oven and a plurality of conical inlets for nitrogen gas 75 in the lining of the oven base.

9. Apparatus for making a block of calcium cyanamide and other materials which 80 comprises an oven base having a side wall section secured thereto, a removable upper side wall section thereon, a refractory lining on the inner surface of the oven and a plurality of conical inlets for nitrogen gas 85 in the lining of the oven base, the small diameter of said inlets being at the upper surface of said base.

10. Apparatus for making a block of calcium cyanamide and other materials which 90 comprises an oven base having a side wall section secured thereto, a removable upper side wall section thereon, a refractory lining on the inner surface of the oven and a plurality of inlets for nitrogen gas 95 in the lining of the oven base substantially uniformly distributed over the surface of said base.

In testimony whereof, I have hereunto subscribed my name this 15th day of June, 1925.

GEORGE E. COX.
